BANDAGE STRIP DISPENSER OR THE LIKE

Anthony Restaino and Joseph Mazzuka, Brooklyn, N.Y.

Application July 26, 1957, Serial No. 47,090

Term of patent 14 years

(Cl. D52—2)

FIG. 1.

FIG. 2.

FIG. 5.

FIG. 3.

FIG. 4.

Figure 5 is an end elevational view thereof, both ends of the dispenser being similar in appearance.

We claim:

The ornamental design for a bandage strip dispenser or the like, substantially as shown and described.
